UNITED STATES PATENT OFFICE.

LOUIS ALLIS, OF MILWAUKEE, WISCONSIN.

ANIMAL TOY.

1,149,170.

Specification of Letters Patent. Patented Aug. 10, 1915.

Application filed April 26, 1915. Serial No. 23,795.

To all whom it may concern:

Be it known that I, LOUIS ALLIS, a citizen of the United States, and resident of Milwaukee, in the county of Milwaukee and State of Wisconsin, have invented certain new and useful Improvements in Animal Toys; and I do hereby declare that the following is a full, clear, and exact description thereof.

10 My invention has for its primary object to provide a simple and economical animal toy having a body, in some form, composed of pliable material that is impregnated with a substance appealing to one or more senses 15 of the animal, whereby the durability of the toy is insured in order that said toy will resist disintegration under chewing strain, to which it is subjected.

This toy may be used by various types of 20 animals and is particularly adapted for use of dogs, the design being immaterial as, for example, I may, in some instances, use a tubular form or a solid cylindrical form, polygonal, spherical or ring-like, without 25 departing from the spirit of my invention.

Specific objects of my invention are to provide an article of the above described character the body of which is formed from some pliable fibrous material of sufficient 30 toughness to resist wear or disintegration caused by constant chewing of the animal, the said body fiber being impregnated in a suitable manner with some substance that will appeal to the sense of smell or taste of 35 the animal, which substance may have either nourishing or medicinal properties or both so commingled with the body as a vehicle as to form a solid mass of convenient shape that is palatable, but practically indestructible; 40 to provide a body or vehicle of substance that is either woven with or without some ligature or binding material such as rubber or the like, or the vehicle body may be composed of fiber combined with the binder to 45 cause the fiber to adhere in a solid mass that will resist rough usage to which it may be subjected by an animal at play, or the vehicle body containing palatable matter may be composed of either vegetable or mineral 50 fiber in some instances.

With the above objects in view the invention consists in what is herein shown, described and claimed.

In the drawings Figure 1 represents an 55 elevation of a toy in tubular form embodying the features of my invention; Fig. 1^a, a

cross-section of the same; Fig. 2, an elevation of another form of toy wherein fiber is employed and so interwoven as to eliminate a second binder element; Fig. 3, a perspective view of a toy embodying the features of my invention which is shown in rectangular form, and Fig. 4 a spherical form of toy embodying the features of my invention.

Referring by characters to the drawings 65 with especial reference to Figs. 1 and 1^a, 1 represents the outer surface of a cylindrical section, which surface is composed of rubber or analogous material forming a coating for an outer layer of woven fiber 2, 70 there being a series of such layers 2', which are bound together by the rubber material in a manner similar to that employed in constructing tubular hose. When the article is in the process of manufacture, either the 75 fibrous body or binder or both are treated with a substance which is appealing to at least one of the senses of an animal, as, for example, this substance may comprise some saccharine product or some substance having 80 medicinal properties that are desirable for the health of the animal. For example, in the treatment of dogs, in some instances, sulfur may be used, or strychnine in small quantities. These articles may be made up 85 in quantities containing various medical properties for the treatment of animals, consistent with certain seasons of the year. It is apparent that an article so manufactured is tough and pliable and an animal may 90 chew upon it from time to time and utilize it as a toy, which will resist disintegration for a long period of time and the taste of the toy to the animal is palatable, whereby a certain amount of nourishment or medicine 95 will be taken up in the system, due to the chewing and saliva which renders the article exceedingly tasteful to the animal, thus not only affording amusement but 100 healthful results will attain.

The vehicle or body of each toy is, under all conditions, composed of some pliant material which will resist chewing strain and, for example, in place of utilizing canvas or woven fiber in conjunction with a binder of rubber, I may, without departing from the spirit of my invention, impregnate a section of woven fiber rope A, as shown in Fig. 2, with a substance that may appeal to any one or all of the senses of an animal.

Attention is called to the fact that, in practice, the animal will naturally chew the

ends of the tubular or cylindrical toy and that in so doing the fibrous body will become exposed and to a certain extent unraveled if woven. This gradual reduction of the ends will permit access to the substance which it contains, for nourishment or treatment of the animal medicinally and after the chewed end has lost its nourishing or medicinal properties, it may be cut off to present a fresh end upon which the animal may chew. This toy also further assists in keeping the animal's teeth in good condition.

Fig. 3 illustrates a polygonal column B which is composed of woven fiber layers 3 with an adhesive binder 4 therebetween, which binder also forms an outer sheath for the composite toy. It is also within the scope of my invention to utilize woven fiber and some ligature or binder in such manner that the two elements are rolled one upon the other, being impregnated with the desired substance either medicinal or nourishing.

Fig. 4 shows a ball C that is composed of fibrous material 5 and a suitable binder 6.

Various other forms may be employed for carrying out my invention without departing from the spirit of the same.

Copies of this patent may be obtained for five cents each, by addressing the "Commissioner of Patents, Washington, D. C."

I claim:

1. An animal toy comprising a pliant body impregnated with a substance appealing to the taste and smell of the animal.

2. An animal toy comprising a pliant body impregnated with a palatable substance.

3. An animal toy comprising a pliant fibrous body impregnated with a palatable substance.

4. An animal toy comprising a pliant body, and a binder for the body, the said body elements being impregnated with a substance appealing to the smell and taste of the animal.

5. An animal toy comprising a pliant fibrous body, a cohesive binder for the same, the said composite body being impregnated with a palatable substance.

In testimony that I claim the foregoing I have hereunto set my hand at Milwaukee in the county of Milwaukee and State of Wisconsin in the presence of two witnesses. 50

LOUIS ALLIS.
